(57) **CLAIM**

The ornamental design for a decoration as shown and described.

DESCRIPTION

FIG. 1 is a front, right and top perspective view of a decoration, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another front, right and top perspective view thereof, shown in another state of use.

The broken lines shown in the drawings are included for the purpose of illustrating portions of the decoration that form no part of the claimed design.
